BOAT

Joseph W. Holloway, Longview, Tex., assignor to Stemco
Manufacturing Company, Inc., Longview, Tex.

Filed Jan. 15, 1963, Ser. No. 73,187

Term of patent 14 years

(Cl. D71—1)

FIG. 1

FIG. 2

FIG. 4

FIG. 3

FIG. 1 is a side elevational view of a boat embodying my new design.

FIG. 2 is a plan of the boat shown in FIG. 1;

FIG. 3 is a stern elevation of the same boat; and

FIG. 4 is a bottom plan view thereof.

The characteristic features of my design reside in the color contrasting areas indicated by shading in combination with the substantially V-shaped sides, upstanding rim around the open cockpit and a downward and outward extending narrow rectangular body element at the bow between converging sides.

I claim:

The ornamental design for a boat, substantially as shown and described.
